(57) CLAIM

The ornamental design for a knitted hip wrap, as shown and described.

DESCRIPTION

FIG. 1 is a front perspective view of a first embodiment of the knitted hip wrap;

FIG. 2 is a front view thereof;

FIG. 3 is a rear view thereof;

FIG. 4 is a left side view thereof;

FIG. 5 is a right side view thereof;

FIG. 6 is a front perspective view of a second embodiment of the knitted hip wrap;

FIG. 7 is a front view thereof;

FIG. 8 is a rear view thereof;

FIG. 9 is a left side view thereof; and,

FIG. 10 is a right side view thereof.

The broken lines in the drawings depict environment that form no part of the claim. The broken lines shown on the side of the knitted hip wrap in FIGS. 4 and 9 depict stitching that forms no part of the claim.

1 Claim, 10 Drawing Sheets
